KEYHOLE LOCK

John Elsberg, New York, N. Y.

Application March 6, 1950, Serial No. 147,940.

2 Claims. (Cl. 70—424)

1

This invention relates to a key hole lock.

It is an object of the present invention to provide a key hole lock adapted to be inserted in a key hole and prevent the admission to the key hole of a key from the outside and to prevent tampering with the door lock and thereby to provide means which cannot be removed from the key hole in order to permit the key of one attempting to enter the room from being used.

Other objects of the present invention are to provide a key hole lock which is of simple construction, inexpensive to manufacture, has a minimum number of parts, easy to insert and remove from the key hole and efficient in operation.

For other objects and for a better understanding of the invention, reference may be had to the following detailed description taken in connection with the accompanying drawing, in which

Fig. 1 is a perspective view of the key hole lock embodying the features of the present invention.

Fig. 2 is a perspective view of the slide in its released position adapted to prevent the easy removal of the key hole lock from the inside of the room having the door.

Fig. 3 is a longitudinal sectional view taken on line 3—3 of Fig. 1.

Fig. 4 is an elevational view showing the key hole lock being inserted within a key hole and the latching member elevated, the slide being in its original position.

Fig. 5 is a view similar to Fig. 4, but with the slide having been adjusted upon the operating member and latched with the operating teeth thereof.

Referring now to the figures, 10 represents the main body formed of a strip of material bent into U-shape and an internal member 11 which has an inclined edge 12 and is secured by pins 13 and 14 to the open under side of the body 10. The member 11 has a depending projection 15 adapted to engage with the lock face in the door to prevent the further inward projection of the device. The body carries a slide or operating member 16 and a latch hook 17 that is lifted by the slide as the operating member is pulled by its handle 18 inwardly. The latch hook 17 is pivoted to the main body 10 by a pin 19. A leaf spring 21 reacts between the closed folded upper portion of the body 10 to urge the latch hook 17 downwardly onto the slide 16. The slide 16 has a curved upper edge 22 that serves as a cam to effect the lifting action of the latch

2

hook 17. The member 11 having the inclined edge 12 extends inwardly beyond the folded strip of the body in order to provide adequate support for the operating member 16.

5 The operating member 16 has an elongated slot 23 through which extends a pin 24 carried by the body and whereby the operating member will be limited in its inward and outward movement with respect to the main body.

10 The upper edge of the operating member has rack teeth 25 adapted to receive a slide lock 26. The slide lock 26 reacts against the edge of the body 10 so as to keep the operating member in its pulled out position and the hook latch 17 elevated.

Once the key hole lock is inserted and the parts are adjusted to elevate the hook latch 17, any insertion of a key on the outer side of the door is prohibited and there is provided a stop 20 which cannot be readily released from the door.

The slide lock 26 comprises a slotted member 28 having slot 29 and portions 31 adapted to enter spaces between the teeth 25. When the lock slide 26 is not in use, it can be secured in a wide 25 notch 32 on the operating member 16. The slotted member 28 is held in place when a pivot arm 33 with its projection 34 is lowered so that the projection 34 enters a hole 35 in the side of the slotted member 28 so as to engage with the 30 under edge of the operating member 16 and prevent the upward displacement of the slide lock. A pin 36 prevents the removal of the lock slide 26 from the operating member 16.

While various changes may be made in the detail construction, it shall be understood that such changes shall be within the spirit and scope of the present invention as defined by the appended claims.

Having thus set forth and disclosed the nature of my invention, what is claimed is:

40 1. A key hole lock comprising a body member, a slide forming an operating member operable in the body member and having a cam surface, a hook latch pivotable in the body member and co-acting with the cam surface of the operating member to be operated, said operating member being longitudinally adjustable through the body member, and a slide lock device on the operating member adapted to hold the operating member against inward displacement relative to the body member when the latch has been projected, and said operating member having ratchet teeth, said slide lock having portions entering spaces between the ratchet teeth whereby to 45 positively lock the slide lock against longitudinal

displacement upon the operating member, said slide lock having a pivot latch thereon engageable with the operating member to hold the slide lock device against lateral displacement once said portions thereof are disposed in the spaces between the ratchet teeth.

2. A key hole lock comprising an elongated body member having an opening extending longitudinally therethrough, a slide member extending adjustably through the opening in the 10 body member and having a concave cam surface along a portion of the upper edge thereof, an elongated hook latch pivoted at one end in the body member and extending with its other end out through said opening thereof above 15 the cam surface of the slide member, a spring in said body member biasing said hook latch down toward said cam surface on said slide member, the latter having a series of teeth along another portion of the upper edge thereof, a slide lock device movably straddling said slide member and having two downwardly extending edge portions spaced apart and adapted to seat in and engage with the teeth upon said slide mem- 20 ber in order to prevent longitudinal displace- 25

ment of the latter with respect to said body member, a latch hinged to said slide lock device in a position to swing into and from a latching position about a substantially horizontal pivot axis parallel to the longitudinal dimension of said slide member, said slide lock device having a side aperture below the level of the lower edge of the slide member, and a locking projection on said latch in effective position to enter said side aperture in latching position of said latch and extend beneath said lower edge of said slide member and prevent raising thereof and disengagement of the downwardly extending edge portions on said slide lock device from the teeth on said slide member.
